WAVE-SIGNAL TRANSLATING SYSTEM

Bernard D. Loughlin, Bayside, N. Y., assignor, by
mesne assignments, to Hazeltine Research, Inc.,
Chicago, Ill., a corporation of Illinois

Original application December 31, 1943, Serial No.
516,394. Divided and this application October
10, 1944, Serial No. 557,953

3 Claims. (Cl. 177—380)

1

This invention relates, in general, to wave-signal translating systems and is particularly directed to coding or secrecy aspects of transponder systems. As used throughout this specification and in the appended claims, the term "transponder system" is intended to describe a wave-signal translating system which includes a receiving system and a transmitting system so arranged that a predetermined answer or reply signal is transmitted in response to a received interrogating signal, the reply and interrogating signals preferably comprising radiant-energy wave signals.

This application constitutes a division of co-pending application Serial No. 516,394, filed December 31, 1943, in the name of Bernard D. Loughlin and assigned to the same assignee as the present invention.

Transponder systems of the type under consideration are frequently utilized as beacons for supplying direction-finding information to air traffic. In the usual installation the system is designed to translate pulse-modulated wave signals in a pulse-by-pulse fashion. That is, the receiving system is designed to receive a radiated interrogating signal having pulse-type characteristic variations, such as pulse-type amplitude variations, and the transmitting system is designed to transmit a reply signal having similar characteristic variations, their operation being such that each modulation pulse of the received interrogating signal causes the transmission of a single pulse of the reply signal. It has been proposed that the reply signal be coded to render the system secret and thus preclude unauthorized listeners from deriving useful information. The arrangements employed to accomplish this coding have consisted of mechanical devices for so interrupting the normal pulse-by-pulse operation of the transponder system that the transmitted pulses of the reply signal appear in spaced groups in accordance with a prearranged coding schedule.

While the described coding arrangements have proved satisfactory, they require that the interrogating signal be continuously received by the transponder system for a considerable period of time to insure the transmission of a complete coded answer. In some installations, this time requirement may be an undesirable limitation. This is especially true where the complete coded reply must be transmitted in the shortest possible period of time.

Furthermore, in certain installations it is desirable that a complete coded reply signal be transmitted in response to a single received pulse

2

of an interrogating signal. The prior art arrangements referred to above do not lend themselves particularly well to such installations.

It is an object of the invention, therefore, to provide an improved wave-signal transponder system which avoids one or more of the above-mentioned limitations of prior art arrangements.

It is a further object of the invention to provide an improved transponder system for transmitting a coded reply signal in response to a received interrogating signal.

It is a further object of the invention to provide a wave-signal transponder system which includes improved coding arrangements in its transmitting system.

In accordance with one feature of the invention, the transponder system includes a wave-signal translating system for translating a signal pulse. This translating system comprises an input circuit for receiving the signal pulse and means coupled to the input circuit for deriving from the received signal pulse a plurality of pairs of signal pulses occurring in a predetermined time sequence and individually having a predetermined time separation. The system further includes means responsive to the plurality of pairs of signal pulses for deriving a pulse-modulated output signal comprising components having pulse durations determined by the time separation of the individual signals of each of the aforesaid pairs and pulse spacings determined by the aforesaid time sequence. This output signal is suitable for controlling a transmitter included in the transponder arrangement to transmit a coded reply signal of similar wave form.

For a better understanding of the present invention, together with other and further objects thereof, reference is had to the following description taken in connection with the accompanying drawings, and its scope will be pointed out in the appended claims.

Fig. 1 of the drawings is a schematic circuit diagram of a wave-signal transponder system including an arrangement, in accordance with the invention, for transmitting a coded reply signal in response to a received interrogating signal; Figs. 2 and 3 comprise graphs utilized in explaining the operation of the arrangement of Fig. 1; Fig. 4 represents a portion of the Fig. 1 arrangement in modified form; while Fig. 5 comprises a set of graphs utilized in explaining the operation of the Fig. 4 arrangement.

Referring now more particularly to the drawings, there is represented in Fig. 1 a wave-signal transponder system having improved secrecy features in accordance with the present inven-

tion. For convenience of explanation, the system may be considered as a radio beacon adapted to transmit direction-finding information to interrogating aircraft. As represented, the radio beacon includes a selective receiving system which forms the subject matter of the above-identified copending application. This selective receiving system has an antenna system 10, 11 coupled to a carrier-frequency signal translator or receiver 12. Where the receiver is of the superheterodyne type, the conventional frequency changer, intermediate-frequency amplifiers, band-pass selectors, and signal detector are included in unit 12. Coupled in cascade to receiver 12 are an amplitude limiter 13, a delay-network unit 20 to be described more particularly hereinafter, a clipping amplifier 14, and a keyed multivibrator 15. The band-pass selectors of receiver 12 and the amplitude limiter 13 are arranged, respectively, to limit the frequency components and amplitude of the signal applied to unit 20 in order that this signal may have a predetermined wave form, that is, a predetermined maximum amplitude and predetermined slopes at the leading and trailing edges of its pulse-type amplitude variations. The beacon further includes a transmitting or wave-signal translating system coupled to the output circuit of multivibrator 15. This transmitting system consists of a delay-network unit 40, described more particularly hereinafter, an amplifier 16, a carrier-frequency signal generator and modulator or transmitter 17, and a transmitting antenna 18, 19. Transmitter 17 is normally in a quiescent condition but is energized or controlled by control signals translated through amplifier 16. Elements 10-19, inclusive, may be of any conventional construction and operation. By way of illustration, amplitude limiter 13 may be similar to the limiter arrangement designated 15 of United States Letters Patent 2,271,203, granted January 27, 1942, in the name of Jasper J. Okrent, and assigned to the same assignee as the present invention. Clipping amplifier 14 may constitute an amplifier biased to pass only signal components having an amplitude value exceeding a critical level, as illustrated at page 372, Fig. 217B of "Principles of Television Engineering," by Donald G. Fink, published in 1940 by McGraw-Hill Book Company, Inc. Multivibrator 15 may be a trigger circuit of the type shown at page 176, Figs. 4-9 of "Ultra-High-Frequency Techniques," by J. G. Brainerd et al., published in 1942 by D. Van Nostrand Company, Inc.

Neglecting for a moment units 20 and 40 and considering element 16 to be a conventional amplifier, it will be readily apparent to those skilled in the art that the arrangement of Fig. 1 comprises a conventional radio beacon. Since the operation of such apparatus is generally well understood, a detailed description and explanation thereof is unnecessary. Briefly, however, an aircraft desiring to obtain information from the beacon sends out an interrogating signal having pulse-type amplitude variations of equal pulse durations and equal pulse spacings. This signal is intercepted by antenna system 10, 11 and translated by receiver 12, the modulation components of the signal appearing in the output circuit thereof as a unidirectional signal having amplitude variations corresponding to those of the received signal. This signal is applied by way of elements 13 and 14 to keyed multivibrator 15, which generates a single control pulse of rectangular wave form and of any desired pulse duration as determined by the circuit pa-

rameters of the multivibrator, one such control pulse being generated thereby in response to each modulation pulse of the interrogating signal. The control pulses from multivibrator 15 are translated through amplifier 16, thereby to control transmitter 17 to transmit in response to each such control pulse a single pulse of an answer or reply signal, the transmitted pulses having substantially the same pulse duration, spacings and wave form as those translated through amplifier 16. Thus, the described transponder system, when interrogated by an inquiring aircraft, transmits a reply signal having pulse-type amplitude variations which individually correspond to modulation pulses of the interrogating signal. Expressed differently, the beacon functions in a pulse-by-pulse fashion to transmit an answer in response to an interrogating signal.

Referring now more particularly to the delay-network units 20 and 40 of the Fig. 1 arrangement, these units are associated, respectively, with the receiver and transmitter portions of the transponder system, being provided to afford the desired secrecy characteristics. Unit 20 is a transversal time-delay filter network having input terminals 21, 21 and output terminals 22, 22. The delay network comprises a transmission line consisting of a pair of spaced parallel conductors 23, 23, coupled at one end to input terminals 21, 21, and terminated at the opposite end in the surge or characteristic impedance of the line designated 24. The electrical characteristics of transmission line 23, 23, are preferably such as to effect a uniform predetermined time delay per unit of line length to a signal translated thereby. The physical length of the line is determined by the degree of secrecy desired, as will presently be explained. A plurality of adjustable taps are associated with the line so as to be freely movable therealong, three such taps 25, 26 and 27 being shown in the drawings. Each of taps 25, 26 and 27 is included in circuit with an individual one of isolating resistors 28, 29 and 30 and a common impedance 31 is coupled between output terminals 22, 22, of unit 20. Each isolating resistor has a relatively high impedance as compared with that of common impedance 31.

Unit 40 likewise comprises a transversal time-delay filter network having input terminals 41, 41, output terminals 42, 42, a parallel-conductor transmission line 43, 43, coupled at one end to terminals 41, 41 and terminated at the opposite end in its surge or characteristic impedance 44. Transmission line 43, 43, may be of the same general construction and design as line 23, 23, of unit 20. Unit 40 also includes a plurality of adjustable taps 45, 46 and 47 adjustably connected to transmission line 43, 43, isolating resistors 48, 49 and 50 individually in circuit with each of the taps, and a common output impedance 51 having a low value of impedance in comparison with that of the individual isolating resistors. Impedance 51 of this arrangement is coupled between the output terminals 42, 42.

In considering the effect of units 20 and 40 on the described operation of the transponder system of Fig. 1, it will be assumed initially that only a single tap is effective in each of such units, namely, tap 25 of unit 20 and tap 45 of unit 40. It will be further assumed that these taps are positioned adjacent to the input terminals of their respective units, as illustrated. For the assumed condition, a received interrogating signal is translated directly from wave-signal translator 12 through unit 13, tap 25 of unit 20 and amplifier

14 to multivibrator 15. Also, the control pulses generated in multivibrator 15 are translated directly therefrom through tap 45 of unit 40 to amplifier 16 and transmitter 17. Accordingly, for these conditions the operation of the transponder system is substantially as described.

Now it will be assumed that all of the taps of units 20 and 40 are effective and that such taps are positioned along their associated transmission lines in the manner indicated in the drawings. It will be further assumed that clipping amplifier 14 is adjusted to have a clipping level indicated by broken-line curve *c* of Fig. 2 and that the interrogating signal as applied to input terminals 21, 21, of unit 20 has the wave form represented by curve *e₂₅*, of Fig. 2. From this last-mentioned curve, it will appear that the interrogating signal as applied to terminals 21, 21, has a maximum amplitude limited to a predetermined value *e* by unit 13 and a group of three pulse-type amplitude variations of equal pulse durations *t* occurring in a predetermined time sequence represented by the unequal pulse spacings *t₁* and *t₂*. It will be understood that the interrogating signal may comprise repeating groups of pulse-type amplitude variations individually having pulse durations and spacings as described and a time separation which is long with reference to the period of a single group. For convenience of explanation, however, the interrogating signal will be considered as consisting of but a single group of such amplitude variations.

The response of the transponder system to such a received signal is illustrated by the curves of Figs. 2 and 3 in which the subscripts indicate the elements where the represented signal voltages are derived. Signal voltages are derived at each of taps 25, 26 and 27. If the signal attenuation along line 23, 23 be neglected, the derived signal voltages individually have a predetermined maximum amplitude equal to the above-mentioned value *e* and pulse-type amplitude variations corresponding to the modulation of the received interrogating signal. Due to the time-delay characteristics of transmission line 23, 23, and the relative spacings of the adjustable taps, these signal voltages have a time relation with reference to each other such that predetermined amplitude variations of the several signal voltages occur substantially in time-phase relation. More specifically, the third amplitude variation of signal *e₂₅*, the second amplitude variation of signal *e₂₆*, and the first amplitude variation of signal *e₂₇* occur in time-phase relation. These signals add up across load impedance 31, producing an output signal at terminals 22, 22, as represented by curve *e₂₂*, having one amplitude variation or pulse of such magnitude as to exceed the clipping level *c* of clipping amplifier 14. This amplitude variation of the output signal corresponds in time with the above-described in-phase components of the individual signals obtained at taps 25, 26 and 27 and produces a control effect which keys multivibrator 15.

The multivibrator generates and applies to input terminals 41, 41, of unit 40 a single unidirectional pulse of substantially rectangular wave form. The time-delay characteristics of transmission line 43, 43, cause taps 45, 46 and 47 to 70 derive a plurality of signals individually having a wave form corresponding to that of the applied pulse and a time relation with reference to each other such that the signals derived at the individual tapping points appear in a pre-

determined time sequence. These signals develop across the common impedance 51 a control signal, represented by curve *e₄₂* of Fig. 3, for application to amplifier 16. This control signal likewise has pulse-type amplitude variations of equal pulse durations *t₄* determined by the period of multivibrator 15 and unequal pulse spacings *t₅* and *t₆* determined by the relative positions of taps 45, 46 and 47. The reply signal transmitted from antenna system 18, 19 in response to this control signal is a pulse-modulated signal comprising components having pulse durations and pulse spacings corresponding to those of control signal *e₄₂*. In other words, the transponder system including units 20 and 40 with taps arranged as indicated in the drawings responds to interrogating signals having pulse-type amplitude variations occurring in the order mentioned and transmits in reply thereto a complete coded answer, coded in accordance with the relative settings of the taps included in unit 40.

From the foregoing description, it will be apparent that the arrangement of Fig. 1 comprises a wave-signal transponder system for transmitting a coded reply signal in response to an interrogating signal having characteristic variations appearing in a predetermined time sequence. With reference to the particular coded reply signal transmitted, unit 40 comprises means for deriving from the interrogating signal a plurality of signals individually having predetermined characteristic variations and a time relation with reference to each other such that predetermined variations of the individual characteristics of the plurality of signals appear in a predetermined time sequence, which may be the same or different from the time sequence of the characteristic variations of the interrogating signal. Furthermore, amplifier 16 and wave-signal generator and modulator 17 comprise means responsive to the predetermined variations of this plurality of signals for transmitting a coded reply signal having components corresponding in number to this plurality of signals and a spacing determined by the time sequence of such plurality of signals.

A modification of the coding arrangement for the transmitter portion of the transponder system is represented in Fig. 4 and indicated generally as 40'. This arrangement is similar in construction and design to unit 40, described above, and corresponding components thereof are designated by like reference numerals primed. However, unit 40' includes a second series of adjustable taps 45'', 46'', and 47'' as well as isolating resistors 48'', 49'', and 50'' and a common impedance 51''. The input circuit of a phase inverter 70, such as a triode amplifier with unity gain, is coupled across impedance 51'' and the signal derived in the output circuit thereof is applied to the input terminals of an integrating circuit 71 along with the signal voltage developed across common impedance 51''. The integrating circuit may be of the type shown at page 163, Fig. 95 of "Principles of Television Engineering." The output terminals 42', 42' of unit 40' are coupled to the output terminals of integrating circuit 71.

To utilize the described modification of the coding arrangement in the transponder system of Fig. 1, multivibrator 15 is adjusted to generate a sharp pulse of rectangular wave form having a pulse duration *t₁₅*, curve *f* of Fig. 5. This curve demonstrates the time relation of the pulses derived at the individual taps of the trans-

versal time-delay filter network in response to a single pulse applied from multivibrator 15. Phase inverter 10, by inverting the phase of the signals developed at taps 45'', 46'' and 47'', causes the signal delivered to integrating circuit 11 to have a wave form as represented by curve g. It will be noted that this signal effectively comprises a plurality of pairs of signals appearing in a predetermined time sequence and individually comprising unidirectional signals of opposite polarities having a predetermined time separation. That is, for the assumed relative positions of the adjustable taps, the derived pairs of signals have individual time separations indicated t_{16} , t_{17} and t_{18} and appear in a time sequence represented by intervals t_{19} , and t_{20} . The integrated signal obtained at output terminals 42', 42", has a wave form as indicated by curve h and, after translation through amplifier 16, controls wave-signal generator and modulator 17 to transmit a reply signal having a modulation envelope of similar wave form. Thus, unit 40' permits the coded reply signal to have components of predetermined pulse duration and pulse spacings as determined by the selective positioning of the adjustable taps associated with transmission line 43', 43".

The described coding arrangements are extremely flexible and provide a degree of secrecy which increases with the complexities of the particular arrangement utilized. The secrecy features of the transmitter portion may be varied by including any desired number of taps or pairs of taps in the coding arrangement of units 40 and 40', respectively, spaced in accordance with any desired coding schedule. Likewise, the described coding arrangement of the selective receiver may be suitably modified to obtain varying degrees of secrecy, as particularly mentioned in the above-identified copending application.

Although it is preferred that coding arrangements be associated with both the receiver and transmitter portions of the transponder system, either one may be omitted. Where the coding feature is utilized in the transmitter but omitted from the receiver, a complete coded answer is transmitted in response to a single pulse modulation of the interrogating signal.

In any case, where coding of the transmitted reply signal is employed, it is desirable to provide a holding or blocking feature in the receiver to disable the receiver for such a period of time following the tripping of multivibrator 15 that a complete coded reply may be transmitted before an interrogating signal is able to trip the multivibrator a second time. In many applications this feature will be inherent in the receiver since the transmitted signal, which is intercepted by the receiving antenna system 10, 11, in most installations will have such power as to overload the receiver circuits and disable the receiver for a period of time determined by its inherent time constant.

The described transversal time-delay filter networks are especially useful in the coding arrangements under consideration since they permit the coding schedules to be altered through the simple expedient of adjusting the number or relative positions of the adjustable taps. The maximum time delay desired to be obtained in the network governs the lengths of the transmission lines of the described networks.

In the specific modifications of the invention described above, the interrogating signal has been assumed to have amplitude variations appearing in a predetermined sequence. The in- 75

vention is equally applicable to transponder systems designed to receive interrogating signals having pulse-type frequency or phase variations appearing in a predetermined time sequence. Therefore, the expression "an interrogating signal having predetermined characteristic variations appearing in a predetermined time sequence," as used herein, is intended to include all such applications.

10 While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

20 1. A wave-signal translating system for translating a signal pulse comprising, an input circuit for receiving said signal pulse, means coupled to said input circuit for deriving from said received signal pulse a plurality of pairs of signal pulses occurring in a predetermined time sequence and individually having a predetermined time separation, and means responsive to said plurality of pairs of signal pulses for deriving a pulse-modulated output signal comprising components having pulse durations determined by said time separation of the individual signal pulses of each of said pairs and pulse spacings determined by said time sequence.

25 2. A wave-signal translating system for translating a signal pulse comprising, an input circuit for receiving said signal pulse, means coupled to said input circuit for deriving from said received signal pulse a plurality of pairs of signal pulses occurring in a predetermined time sequence and individually having a predetermined time separation, and means including an integrating circuit responsive to said plurality of pairs of signal pulses for deriving a pulse-modulated output signal comprising components having pulse durations determined by said time separation of the individual signal pulses of each of said pairs and pulse spacings determined by said time sequence.

30 3. A wave-signal translating system for translating a signal pulse comprising, an input circuit for receiving said signal pulse, means coupled to said input circuit for deriving from said received signal pulse a plurality of pairs of signal pulses occurring in a predetermined time sequence and individually comprising unidirectional signal pulses of opposite polarities having a predetermined time separation, and means responsive to said plurality of pairs of signal pulses for deriving a pulse-modulated output signal comprising components having pulse durations determined by said time separation of the individual signal pulses of each of said pairs and pulse spacings determined by said time sequence.
